UNITED STATES PATENT OFFICE.

JOSEPH N. MAHONEY AND HOWARD G. MACDONALD, OF WILKINSBURG, PENNSYLVANIA, ASSIGNORS TO WESTINGHOUSE ELECTRIC AND MANUFACTURING COMPANY, A CORPORATION OF PENNSYLVANIA.

SWITCHING DEVICE.

1,370,030.

Specification of Letters Patent.

Patented Mar. 1, 1921.

Application filed May 11, 1914. Serial No. 837,923.

To all whom it may concern:

Be it known that we, JOSEPH N. MAHONEY, a citizen of the United States, and a resident of Wilkinsburg, in the county of Allegheny and State of Pennsylvania, and HOWARD G. MACDONALD, a citizen of the United States, and a resident of Wilkinsburg, in the county of Allegheny and State of Pennsylvania, have invented a new and useful Improvement 10 in Switching Devices, of which the following is a specification.

Our invention relates to switching devices, and particularly to double-throw, automatically operated switches.

15 One object of our invention is to provide a double-throw switch for automatically connecting a receiving circuit to the one or the other of two sources of energy.

Another object of our invention is to provide 20 a selective device for controlling the recurrent operation of a switch, under certain conditions of operation.

Another object of our invention is to provide means for automatically closing the 25 magnetic circuit of an electromagnet, when the same is energized, to prevent undue heating of the windings.

In operations where it is imperative that a continuous service be maintained, it is 30 desirable to supply energy from at least two sources. In order to eliminate the necessity of manually switching from one source of energy to the other when an interruption occurs, we have provided an automatically 35 operated switching device. Since it is desirable, in some cases, to return to the original source of energy when service is resumed, we have provided a selective device which will either permit this or prevent it, 40 at the discretion of the operator.

In the accompanying drawings, Figure 1 is a side view, partially in section and partially in elevation, of a switching device embodying our invention; Fig. 2 is a front 45 view, partially in section and partially in elevation, of the device shown in Fig. 1; Fig. 3 is a detail top plan view of an operating mechanism embodying our invention; Fig. 4 is a detail side elevational view of the 50 mechanism shown in Fig. 3, and Fig. 5 is a diagrammatic view of a switching device embodying our invention.

The switching device 1 comprises a plurality of terminal members 2, 3 and 4, a

plurality of stationary contact members 5 55 and 5^a, which are respectively mounted upon the lower ends of the terminal members 2 and 4, and a plurality of movable contact members 6 and 6^a which are mounted upon a plurality of pivotally mounted arms 7 and 7^a, respectively. The movable and stationary contact members are disposed in an oil-containing receptacle 8, substantially as shown in the drawings. The pivotally mounted arms 7 are operatively connected 65 to the lower ends of two rods 9, the upper ends of which, are operatively connected to a bar 10. The oil-containing receptacle 8 is supported by a frame work 11 which also supports an operating mechanism 12 70 embodying our invention.

The frame work 11 is so shaped as to be suitable for wall mounting and comprises a plurality of standards 13 and 14 for supporting the operating mechanism 12. A 75 bell crank lever 15 is pivotally mounted between the standards 14 upon a pin 16. One of the arms 17 of the lever 15 is pivotally connected to the bar 10 and the other arm 18 is pivotally connected to one end of a 80 link 20 which is pivotally connected, by a pin 21, at a point intermediate its ends, to a link 22. The links 20 and 22 are severally composed of two substantially parallel arms spaced apart and joined at both ends. The 85 link 20 is disposed within the link 22 which is pivotally mounted upon a pin 23 in the standards 13. A downwardly projecting member 24 of the link 22 is provided for co-operating with a lever 25. The lever 90 25 is loosely mounted upon the pin 16 and it is retained in engagement with the member 24 by a spring 26.

An operating electromagnet 27, comprising two coils 28 and 29, a stationary core member 30, and a movable core member 31, is supported by the standards 13 and 14. A forked projection 32, having a pin 33 therein, is attached to the lower side of the movable core member 31. A latch 34 is 100 pivotally mounted upon the pin 33, and a spring 35 is provided for normally retaining the latch in a predetermined position, as shown in the drawings. The latch 34 is provided with a cam face 36 to engage the 105 upper arm of a bell crank lever 37. The engagement of the cam face 36 with the upper arm of the lever 37 causes the latch

34 to become disengaged from the pin 21, for reasons hereinafter set forth. The lower arm of the bell crank lever 37 is connected to a spring 38, and the lever is adapted to 5 be placed in any predetermined position, according to the operation desired, as will hereinafter be more fully described. That is, it may be moved from its normal position to preclude automatic operation of the 10 switching device when desired.

One end of a spring 39 is attached to the lever 15 and its other end is attached to the upper part of the frame work 11, for reasons hereinafter set forth. The link 20 is of such 15 length that the outer end of the same engages the under side of the pin 23 when the toggle mechanism, of which it forms a part, is in its uppermost position.

The windings 28 and 29 of the electro- 20 magnet 27 are connected to a source of energy 40 which we may consider as being connected to the terminal members 4. A receiving circuit 41, to which our device is connected, has its conductors connected to the 25 terminals 3, and a second source of energy 42, to which it is desired to connect the circuit 41 when the first source of energy 40 is interrupted, may be connected to the terminals 2.

30 Assuming the apparatus to occupy the positions shown in the drawings, and that the source of energy 40 has been interrupted, for some reason, the operation of our device is as follows:

35 The movable core member 31 will move downwardly, by reason of the deenergization of the coils 28 and 29, causing the cam face 36 to engage the upper arm of the lever 37, as hereinbefore described. The engagement of the cam face 36 with the upper arm 40 of the lever 37 causes the latch 34 to move in a direction shown by the arrow in Fig. 4. After the pin 21 is disengaged from the 45 latch 34, the projection 32 engages the pin 21 to upset the toggle formed by the members 20 and 22, and the spring 39 moves the arm 17 of the bell crank lever 15 upwardly. The upward movement of the lever 15 causes the rods 9 to move upwardly and the arms 7 and 7^a to rotate. The rotation of the arms 50 7 and 7^a causes disengagement of the contact members 5^a and 6^a, and engagement of the contact members 5 and 6. Since the lever 25 is loosely mounted upon the pin 16, and, since it is connected to the member 24 by a spring 26, it follows the member 24 of 55 the link 22 downwardly and the notch 25^a in the member 25 co-operates with the lug 24^a on the member 24 to cause the same to 60 act as a restraining or toggle device to prevent the disengagement of the contact members 5 and 6 by any jarring which might occur. This toggle is upset only when the member 24 is positively moved upwardly by 65 the latch 34.

If it is desired that the circuit 41, to which our device is connected, be returned to its original source of energy 40 upon a resumption of the same, the bell crank lever 37 is retained in the position shown in the 70 drawings. Then, when the coils 28 and 29 are energized by a resumption of the source of energy 40, the movable core member 31 and the latch 34 will move upwardly and allow the cam face 36 to follow the upper 75 arm of the lever 37 until the latch engages the pin 21 and draws it upwardly. The upward movement of the pin 21 serves to set the toggle device constituted by the members 20 and 22 to thus move the arm 18 in a clockwise direction and to move the arm 17 downwardly. The downward movement of the arm 17 causes the rods 9 to move downwardly to effect engagement of the contact members 5^a and 6^a and disengagement of the contact members 5 and 6. 80

If it is not desired to return to the original source of energy, upon a resumption of the same, the operator turns the selective lever 37 such a distance in a counter-clockwise 90 direction that, when the latch 34 again moves upwardly by reason of the energization of the electromagnet 27, it will not engage the pin 21. The toggle mechanism comprising the members 20 and 22 remains in 95 its lowest position to permit the movable core member 31 to move upwardly without effecting any change in the connections of the circuit 41. The movable core member 31 is allowed to move upwardly, since it is 100 desirable to close the magnetic circuit of an electromagnet, when it is energized, to prevent the coils of the same from being burned out. The member 24 and the lever 25 act as a secondary toggle mechanism 105 when the toggle mechanism is in its lower position, as hereinbefore explained.

While we have described our invention with respect to a particular construction, it is not so limited but is capable of various 110 modifications within the scope of the appended claims.

We claim as our invention:

1. In a switching device for an electrical circuit, the combination with a double-throw 115 switch, of an actuating means, a toggle mechanism operatively connected to the switch, a latch for connecting the toggle mechanism to the actuating means, and a cam device for automatically disengaging 120 the latch from the toggle mechanism when the actuating means reaches its inoperative position.

2. In a switching device for an electrical circuit, the combination with a double-throw 125 switch, of an actuating means, a toggle mechanism operatively connected to the switch, a latch for connecting the toggle mechanism to the actuating means, means for disengaging the latch from the toggle 130

mechanism under predetermined conditions, and means for holding the toggle mechanism in a predetermined position.

3. In a switching device, the combination 5 with a double-throw switch, of an electromagnet for actuating the same in one direction, a spring for actuating the switch in the other direction, a toggle-mechanism operatively connected to the movable member of 10 the switch, means for operatively connecting the electromagnet to the toggle mechanism, and means for disengaging the said connecting means when the electromagnet is deenergized.

15 4. In a switching device for an electrical circuit, the combination with a double-throw switch, of an operating electromagnet therefor, a toggle mechanism operatively connected to the switch, a latch for connecting the 20 toggle mechanism to the electromagnet, and selective means for so controlling the engagement of the latch and the toggle mechanism that they are disengaged when the electromagnet is deenergized and are maintained disengaged upon reenergization of 25 the electromagnet under predetermined conditions.

5. In a switching device, the combination with a switch and an operating electromagnet, of a toggle mechanism operatively connected to the movable member of the switch, a latch actuated by the electromagnet for engaging the toggle mechanism, and means for selectively causing the latch to be disengaged from the toggle mechanism when the electromagnet is deenergized and when it is energized under predetermined conditions.

6. In a switching device, the combination 40 with a double-throw switch, of an operating electromagnet, a toggle mechanism operatively connected to the movable member of said switch, a latch operatively connected to said electromagnet for engaging said toggle mechanism to actuate the same, and automatic means for disengaging said latch from 45 said toggle mechanism when the electromagnet is deenergized.

7. In a switching device, the combination 50 with a double-throw switch, of an operating electromagnet, a toggle mechanism operatively connected to the movable member of said switch, a latch operatively connected to said electromagnet for engaging said toggle mechanism, means for maintaining said 55 toggle mechanism rigidly in an extreme position, and means for disengaging said latch from said toggle mechanisms when the electromagnet is deenergized.

8. In a switching device, the combination 60 with a movable switch member, of an actuat-

ing electromagnet, means for connecting the electromagnet to the movable switch member, and means for automatically disconnecting the connecting means from the movable switch member when the electromagnet is deenergized. 65

9. In a switching device, the combination with a movable switch member, of an actuating means, a toggle mechanism connected to the switch member, means for connecting 70 the actuating means to the toggle mechanism, means for holding the toggle mechanism in an extreme position, and means for disconnecting the connecting means from the toggle mechanism. 75

10. In a switching device, the combination with a movable switch member, of an actuating electromagnet, a toggle mechanism connected to the switch member, means for connecting the electromagnet to the toggle 80 mechanism, and means for automatically disconnecting the said connecting means from the toggle mechanism when the electromagnet is deenergized and under other predetermined conditions. 85

11. In a switching device, the combination with a switch, an actuating electromagnet therefor and a toggle mechanism connected to the switch, of a latch connected to the electromagnet for engaging the toggle mechanism to actuate the switch and a cam member for engaging the latch when the electromagnet is deenergized to disengage the latch from the toggle mechanism, said cam member being adapted to assume such position 90 that, when it is desired, the latch will remain out of engagement with the toggle mechanism upon reenergization of the electromagnet. 95

12. In a switching device, the combination with a switch, an actuating electromagnet therefor and a toggle mechanism connected to the switch, of a latch connected to the electromagnet for engaging the toggle mechanism when it is moved upwardly to 100 set the toggle, means for engaging the latch when the toggle is upset for causing it to disengage the toggle mechanism and for maintaining the latch out of engagement with the toggle mechanism when the latch is again 105 actuated by the electromagnet.

In testimony whereof, we have hereunto subscribed our names this 30th day of April, 1914.

JOSEPH N. MAHONEY.
HOWARD G. MACDONALD.
